BALL JOINTED PEN HOLDER AND THE LIKE

Roland P. Longarzo, Valley Stream, N.Y., assignor to Ibex
Precision Products, Inc., New York, N.Y.

Filed Nov. 15, 1971, Ser. No. 201,632

Term of patent 14 years

Int. Cl. D19—02

U.S. Cl. D74—5 A

FIG. 1

FIG. 2

FIG. 4

FIG. 3

FIG. 5

FIG. 1 is a front elevational view of a ball jointed pen holder, the rear elevational view being similar but without the cutout portion;

FIG. 2 is a top plan view;

FIG. 3 is a bottom plan view;

FIG. 4 is a typical side elevational view, the other side being similar; and

FIG. 5 is a front perspective view thereof as it appears with the ball pen receptacle partially rotated.

I claim:

The ornamental design for a ball jointed pen holder and the like, substantially as shown and described.
